UNITED STATES PATENT OFFICE.

ELMORE C. JORDAN AND CHARLES B. BROWN, OF LOS ANGELES,
CALIFORNIA.

AIR-BRAKE MECHANISM.

No. 839,769.

Specification of Letters Patent.

Patented Dec. 25, 1906.

Application filed February 20, 1906. Serial No. 302,114.

To all whom it may concern:

Be it known that we, ELMORE C. JORDAN and CHARLES B. BROWN, citizens of the United States, residing at Los Angeles, in the 5 county of Los Angeles and State of California, have invented new and useful Improvements in Air-Brake Mechanism, of which the following is a specification.

Our invention relates to that class of air-brake mechanism in which a quick-action triple valve is used for operating the brake mechanism; and the object thereof is to provide means whereby in long trains of cars the braking mechanism of any car in the train 15 of cars can be released by the engineer on the engine without releasing the braking mechanism of cars adjacent to the engine and coupled thereto, and also, if desired, to recharge the auxiliary reservoirs of said car and 20 those adjacent thereto without affecting to any appreciable extent cars closer to the engine.

We accomplish these objects by the mechanism described herein, and illustrated in 25 the accompanying drawing, which is a cross-section of a car equipped with the usual braking mechanism with our improvement applied thereto.

In the drawing, 1 represents a portion of 30 the body of the car, and 2 is the usual braking mechanism, consisting of the usual auxiliary reservoir, brake-piston chamber, and triple valve. These parts are not more fully illustrated because of usual construction and 35 no part of our invention. The triple valve is connected by pipe 3 to the usual train-line 4, through which the braking mechanism is operated in the usual well-known manner. To pipe 3 we connect a pipe 5, which leads to 40 the supplemental train or air pipe 6, which pipe is connected to the air-supply on the engine the same as the train-line 4, except that instead of the usual controlling-valve it is provided in the cab with a three-way 45 valve. On the connection-pipe 5 is a check-valve 7, which prevents the passage of air from pipe 3 to pipe 6 and permits the passage of air from pipe 6 to pipe 3. Pipe 5 is also provided with an ordinary cut-off cock 8, 50 which when closed prevents the passage of air from pipe 6 to pipe 3. It will be understood that the triple valve of each car is connected to the train-line by a pipe similar to

pipe 3 and that under each car the supplemental air-line 6 is connected to such pipe 55 3 by a connecting-pipe 5, provided with a check-valve and a cut-off cock.

In the operation of our device we will assume that a train of fifty cars are equipped therewith and with the usual air-brake 60 mechanism and that the engineer has applied the brakes and desires to release the same. With the present equipment on a train of that character the brake on the first or nearest car to the engine would be released 65 in the usual manner, and thereafter each succeeding car would have its brake released, and the last car in the train would have its brakes released last. In this manner of releasing the brakes as each brake is released 70 the resiliency of the buffer-springs on the car gives the cars in front a forward impetus, which on long trains often causes the couplings to break and sometimes pulls out draft-timbers, thereby delaying the movement of 75 the train. When equipped with our device, before starting out the engineer determines at what parts of his train he desires to have the brakes released. We will assume that he has found by practice that on such a train 80 it is desirable to commence releasing the brakes on the car at the rear end of the train and also on a car twenty-five cars from the rear of the train. In such case he has the stop-cock 8 on the last car and the stop-cock 85 8 on the twenty-fifth car from the rear of the train opened and all the other stop-cocks 8 closed. He then admits a pressure of air into the supplemental train-line sufficient to release the brakes on those cars and keeps 90 the pressure up, whereby the other cars will have their braking mechanism released in the usual manner. At the same time, if desired, he can commence the release of the brakes at the forward end of the train 95 through the main train-line in the usual manner, thereby preventing the breaking of the couplings, because the resiliency of the released buffer-springs has been taken up in different parts of the train, thereby distributing 100 the strain and preventing the whole strain coming on a single coupling.

Having described our invention, what we claim is—

1. In an air-brake mechanism, a supplemental air-line; connections from said sup-

plemental line to the main air-line adjacent to the triple valves; check-valves on said connections, said check-valves preventing main air-line pressure from passing to said supplemental line.

2. In an air-brake mechanism, a supplemental air-line; connections from said supplemental line to the main air-line adjacent to the triple valves; cut-off cocks on said connections; and check-valves on said connections, said check-valves preventing main

air-line pressure from passing to said supplemental line.

In witness that we claim the foregoing we have hereunto subscribed our names this 10th ¹⁵ day of February, 1906.

ELMORE C. JORDAN.
CHARLES B. BROWN.
